UNITED STATES PATENT OFFICE.

GEORGE GODDU, OF WINCHESTER, MASSACHUSETTS, ASSIGNOR TO UNITED SHOE MACHINERY COMPANY, OF PATERSON, NEW JERSEY, A CORPORATION OF NEW JERSEY.

MACHINE FOR INSERTING FASTENINGS.

1,076,279.

Specification of Letters Patent.

Patented Oct. 21, 1913.

Application filed September 3, 1908. Serial No. 451,584.

To all whom it may concern:

Be it known that I, GEORGE GODDU, a citizen of the United States, residing at Winchester, in the county of Middlesex, and 5 Commonwealth of Massachusetts, have invented certain Improvements in Machines for Inserting Fastenings, of which the following description, in connection with the accompanying drawings, is a specification, 10 like reference characters on the drawings indicating like parts in the several figures.

This invention relates to machines for inserting fastenings and particularly to those machines which are designed to handle previously formed fastenings.

An object of the invention is to provide an efficient machine for inserting fastenings which may be manually operated. Power driven fastening-inserting machines have 20 long been known, but the advantages attendant upon the use of such machines, such, for example, as uniformity and rapidity of operation and convenience of manipulation of the work while the fastening is being inserted, have been unattainable to the small manufacturer or to the repair man who had no source of power from which such a machine could be driven. The present invention aims therefore to provide a machine 25 which is inexpensive to manufacture, which is efficient in operation and which will supply to the small manufacturer or to the proprietor of a repair shop means for mechanically inserting fastenings that may be manually operated.

Although the invention aims primarily to provide a machine which may be manually operated, it will be noted from a consideration of the construction herein disclosed that 40 many of the novel principles of operation which characterize the present invention may be utilized to advantage in power-driven machines.

In the accompanying drawings,--Figure 45 1 is a perspective view of a machine embodying this invention, a portion of the standard being broken away in order that the more essential features may be illustrated upon a larger scale; Fig. 2 is a side elevation of 50 the machine illustrated in Fig. 1, the parts being shown in operative relation to each other and the driver being shown as raised into its uppermost position and about to be released to drive a fastening; Fig. 3 is a detail view of the raceway-actuating mecha-

nism; Fig. 4 is a detail sectional view showing the fastening raceway in its fastening-delivering position; Fig. 5 shows the raceway in the position in which it rests temporarily before having imparted to it by its actuating mechanism a sudden movement into fastening-receiving position; Fig. 6 is a detail sectional view showing the fastening raceway in its fastening-receiving position, and showing the operation of the shank-push attachment upon said raceway; Fig. 7 is a perspective view, partly in section, of the fastening supporting ledge, adjacent to the driver passage and of the adjacent end of the fastening raceway; Fig. 8 is a transverse section through the lower part of the fastening container and through the fastening raceway; Fig. 9 shows the novel form of edge gage used in this machine in the two positions to which it may readily be moved; and Fig. 10 shows a bottom-supporting gage, and the manner of using it to obtain a straight line of fastenings across a shoe sole.

In the lower part of a base or standard 2 is fulcrumed at 4 a treadle lever 6 which constitutes, in the illustrated embodiment of the invention, the manually operated means for actuating the various mechanisms hereinafter to be described. The illustrated 25 treadle lever is arranged to operate as a lever of the second class, and the end adapted to be engaged by the foot of the operator is maintained normally in its uppermost position by a spring 8 connected at one end to 30 said lever and at its other end to the standard 2.

Pivoted upon the upper end of the standard 2 is a head 10 maintained normally in its uppermost position by a spring 12 resting at one end in a socket 14 in the head 10 and at its other end in a socket 16 in the standard 2. The head 10 is arranged to be turned about its pivot into work-clamping relation to a piece of work supported upon 45 any suitable work support, such, for example, as a horn 18 rotatable about a center coinciding substantially with the center of its tip.

At its forward end the head 10 is provided 50 with a driver passage 20 enlarged at its upper end to receive a driver bar 22, to which the driver 21 is attached, said bar being arranged to be depressed by a spring 24 to effect the driving of a fastening after it 55

has been lifted against the tension of said spring by means hereinafter to be described. The driver bar 22 has adjustably fastened upon its upper end a head 26 which limits the descent of the driver by engaging a cushion 28 surrounding the driver passage 20 at its upper end and which is also provided with a depending lug 30 adapted to be engaged by a driver-lifting pawl 32 pivoted to turn about a center corresponding with the center of a boss 34 upon the forward end of a lever 36 attached to a rock-shaft 38 mounted in bearings in the head 10. A spring 40, surrounding the boss 34 and bearing at one end against a lug 42 upon the pawl 32 and at its other end against a lug 44 upon the lever 36, presses said pawl normally toward the lug 30 upon the head 26, a lip 46 upon the pawl 32 limiting the movement of the pawl toward the driver. The pawl 32 is provided with a tail 48 arranged to engage a pawl-tripping lug 50 upon an upstanding portion 52 of the head 10 when the driver bar 22 has been raised by said pawl into its uppermost position, whereby the pawl is turned about its pivot into the position shown in dotted lines in Fig. 2, thus releasing the driver bar 22 and permitting it to be depressed by the spring 24 to effect a fastening-driving operation. The spring 24 is confined by a set screw 54 in a socket in the upper end of the upstanding portion 52 of the head 10.

The lever 36 and rock-shaft 38 are turned in a direction to cause the pawl 32 to lift the driver bar 22 by a rod 56 connected at one end to the other arm of the lever 36 and at its other end to the treadle lever 6. The fulcrum of the lever 36, which, in this instance, is the bearing for the rock-shaft 38, is located between the pivot of the head 10 and the driver bar 22, so that when the lever 36 starts to turn in the direction to lift the driver bar 22 the resistance of the spring 24 to the lifting of the driver, acting through the bearing of the rock-shaft 38, tends to depress the forward end of the head 10 against the tendency of the spring 12 to maintain it in its uppermost position and the relative strengths of the springs 24 and 12 are such that, with the leverage obtained by the relative locations of the pivot of the head 10, the spring 12 and the bearing of the rock-shaft 38, the forward end of the head will be depressed into contact with the upper surface of the work supported upon the horn 18 before the driver bar 22 will be lifted to any substantial extent.

Since the spring 24 is mounted upon the head 10 in such a position that any force imparted to its forward end in an upward direction exerts considerable leverage upon the head, and since a sudden force like that caused by rebound of the driver upon strik-

ing a fastening which is to be driven into 65 comparatively hard work would be especially difficult to control in such a manner that the head would hold the work properly clamped if the spring were arranged to follow the driver bar throughout its movement, it is 70 preferable that the impelling force of the spring cease before the driver reaches its lowermost position, and therefore, in the illustrated construction, the driver is arranged to travel through the last part of its 75 driving movement under its acquired momentum, the head 26 upon the upper end of the driver bar being provided with lugs 58 and 60 between which the forward end of the driver spring 24 is confined and guided. 80

In order further to prevent the release of the work by the head at the time the fastening is driven, means is provided for effecting substantially a positive clamping of the work just at this time. As hereinbefore 85 pointed out, the initial clamping of the work is differentially effected during the lifting of the driver against the tension of its spring 24. As the driver will always be released at the same point in the angular movement of 90 the lever 36, a pin 62 has been provided upon the upstanding portion 52 of the head 10, with which the lever 36 engages, just at the time when the pawl 32 releases the driver bar 22, so that the downward pull of the rod 95 56 connected with the treadle 6 will be applied directly to the head 10 through the bearing of the rock-shaft 38. The head will thus be prevented from rising to release the work at the time the fastening is driven. 100

The machine herein illustrated is arranged to drive headed fastenings of the type commonly called "loose nails," and these nails are placed in a fastening container or nail pot 64 attached to the side of the head 10 105 and having a bottom inclined toward said side. The back part of the nail pot 64 is formed upon the arc of a circle, and pivoted in the head 10, so that it oscillates up and down along the inner side of the pot, is a 110 segment-shaped plate 66 having attached to, or formed in, its upper edge a fastening raceway 68 adapted to receive fastenings when in its lowermost position in the pot and to be inclined as the segment-shaped plate 66 115 oscillates into its uppermost position, so that the fastenings slide down it until the endmost fastening comes in contact with the driver 21, the driver passage being formed adjacent to the end of the raceway with a 120 fastening-receiving opening.

As shown, especially in Figs. 4, 5, 6 and 7, the fastening-receiving opening in the driver passage is provided with a ledge 70 inclined downward toward the driver passage and 125 adapted to support by its head a single nail as it is delivered to it by the inclination of the raceway. The segment plate 66 is at-

tached at its center of oscillation to a rock-shaft 72 mounted in bearings in the head 10, and rocking movement is imparted to said rock-shaft through connections to the rock-shaft 38. The illustrated connections comprise an arm 74 rigidly attached to the rock-shaft 38 and having a pin 76 bearing against a spring 78 in a slot in one end of a link 80 connected at its other end to an arm 82 rigidly attached to the rock-shaft 72.

Loosely carried upon the rock-shaft 38 is a catch 84 having a hooked end 86 arranged to engage, when the parts are in proper position, a notch 88 in the link 80. When the parts are in the position shown in Fig. 1, the hooked end 86 of the latch 84 will lie somewhat in front of the notch 88 in the link 80, or to the right of said notch as shown in this figure, and, as the rock-shaft 38 is turned to effect a lifting of the driver bar 22, the pin 76 upon the arm 74 will press against the spring 78 in the slot in the link 80 and move the link in a forward direction, thereby causing the arm 82 to turn the rock-shaft 72 in a clockwise direction in Fig. 3, whereby the raceway 68 is moved toward the bottom of the nail pot 64.

Before the raceway reaches its lowermost position with respect to the nail pot 64, the hook 86 upon the latch 84 will engage the notch 88 in the link 80 and thus prevent the forward movement of the link under the pressure of its spring 78, and the spring will further be compressed in the slot by the action of the pin 76 upon its rearmost end. After the spring has been compressed to a certain extent, an extension 90 upon the arm 74 will engage a pin 92 upon the latch 84 and lift the hook 86 out of the notch 88, thus releasing the stored-up energy in the spring 78 whereby the link 80 is suddenly moved forward and the last part of the movement of the raceway into its lowermost position will be effected suddenly, so that the parts associated with it will be jarred considerably. This movement of the raceway which preferably brings the lower edge of the segment plate 66 into engagement with the portion of the head 10 in which the driver passage 20 is formed will aid in jarring the nail resting upon the ledge 70 into the driver passage and will serve also to shake down nails in the nail pot so that the raceway may receive a new supply for the next fastening-delivering operation.

As hereinbefore pointed out, the ledge 70 is inclined downwardly toward the driver passage so that when the head of the nail rests upon it the shank of the nail has a tendency to tip away from the driver while the edge of the head rests against it. When the driver is raised, the friction or "drag" between the head of the nail and the driver tends to turn the shank toward the driver.

To insure, however, the proper delivery of the nail to the driver passage, the segment plate 66 which carries the raceway 68 has formed upon, or attached to, its lower edge a shank-pushing and guiding projection 94 which engages the shank of the nail resting upon the ledge 70 and moves it toward a position of parallelism with the driver 21, in case it has not already been moved into such position by the above-mentioned drag of the driver upon the nail head, and as the raceway is given its sudden movement into its lowermost position gives to the shank of the nail a sudden push toward the driver passage which has then been cleared by the upward movement of the driver.

For convenience, the segment plate 66 and its associated raceway will together be referred to hereinafter as the raceway.

The fastening container or nail pot is preferably so constructed that the nails or other fastenings may readily be removed when it is desired to use different sizes or kinds, the pot 64 herein shown being provided with a door 95 pivoted at 96 upon the pot and held in closed position by a spring catch 98, a handle 100 being provided for use in opening and closing said door.

For convenience in clearing the driver passage in case a defective fastening becomes stuck in it, the section of the head 10 which includes the portion of the driver passage provided with the fastening-receiving opening is made removable, as shown at 102 in the drawings, and is held in place by a set screw 104.

As hereinabove suggested, the machine is provided with a novel edge gage, the illustrated gage comprising a member 106 having an edge-engaging portion and a portion extending up along the side of the head and provided with a closed slot through which passes a set screw 108 and an open slot in substantial alignment with the closed slot and adapted to receive a headed pin 110 upon the side of the machine head. The open slot is long enough to provide the desired adjustment of the edge gage toward and from the driver passage, but is not so long as to prevent the withdrawal of the slot from engagement with the pin 110 so that the gage may be turned back into the dotted line position shown in Fig. 9.

Upon the other side of the head 10 is provided a novel form of gage intended to be used to aid in driving fastenings in a particular relation to each other when they are not being driven parallel to the edge of the work. The illustrated gage comprises a straight edged member 112 having an attaching portion 114 extending substantially at right angles to the member 112 and provided with a slot 116 through which passes a set screw 118 by which the gage may be con-

fined in adjusted position upon the head 10. In the illustrated construction the slot 116 is of such a length that when the gage member is moved as far forward as the slot 5 will permit it to go, the line of the lower edge of the member 112 includes the driver passage 20. The manner of using this gage is shown in Fig. 10. In this figure is shown a shoe sole into which it is desired to drive 10 a row of nails extending straight across the sole from side to side, and the nails are kept in alinement as they are driven successively by keeping them in line with the edge of the gage member 112. It will be seen from 15 an inspection of the construction shown in the drawings that these gage members can be used together if desired, although it is usually not necessary to use one when the other is being used. It will be understood 20 that this feature of the invention is not restricted to a straight edged gage member.

To prevent nails from lying across the raceway and thus clogging it and at the same time to provide a sufficient thickness to the 25 wall of the raceway upon the side of the slot adjacent to the side of the head 10, this wall is provided above the portion on which the head of the nail rests with an upstanding portion 120 which is high enough above 30 the other wall or side of the raceway to give to nails resting upon the two an inclination such that they will fall off when the raceway rises into fastening-delivering position and which leaves a ledge for the 35 head of the nail to rest upon substantially only wide enough for the overhanging part of said head.

The operation of the machine hereinabove described is as follows: A piece of 40 work having been placed upon the horn 18, such for example as a shoe, as shown in Fig. 2 of the drawings, the operator places his foot upon the forward end of the treadle lever 6 and depresses said lever, thereby 45 through rod 56 turning the lever 36 about its fulcrum and at the same time rocking the rock-shaft 38. As the lever 36 starts to turn in a counter clockwise direction, as viewed in Figs. 1 and 2, the driver-lifting 50 pawl 32 will be raised, carrying with it the driver bar 22, until the head 26 or the upper end of said bar engages the spring 24, when further upward movement of the 55 driver bar 22 and driver-lifting pawl 32 will be substantially prevented by the resistance of the spring 24 until the head 10 has been depressed, by the pull of the rod 56 upon the lever 36 and the bearing of the rock-shaft 38, into engagement with the 60 work, such depression of the head effecting a partial compression of the spring 12.

When the work abutment surrounding the driver passage has been brought into engagement with the upper surface of the

work by the depression of the head, further 65 downward movement of the treadle lever 6 and the rod 56 will serve to lift the driver bar 22 until the tail 48 of the pawl 32 comes into engagement with the pawl-tripping lug 50 upon the upstanding portion 70 52 of the head 10, and the pawl is turned into the dotted line position shown in Fig. 2. This effects a release of the driver 22 which is then depressed by the spring 24 to drive the nail delivered to the driver pas- 75 sage just before the tripping of the pawl 32.

Just as the pawl 32 is moved out of engagement with the downwardly projecting part 30 of the driver head 26, the lever 36 comes into engagement with the pin 62 upon 80 the upstanding portion 52 of the head 10 and the pull of the rod 56 connected with the treadle lever 6 is then exerted directly upon the head 10 so that the head is held in engagement with the work during the 85 nail-driving operation. The nail delivered to the driver passage during this driving operation is one which has been left upon the nail ledge after the treadle lever 6 has been released following the previous nail- 90 driving operation.

When the treadle lever is depressed to raise the driver bar 22 in advance of the nail-driving operation, the raceway will be oscillated through its connections with the 95 rock-shaft 38 into its nail-receiving position and, as hereinbefore described, the last part of this movement into nail-receiving position just as the driver rises above the nail-supporting ledge 70 will be effected quickly 100 so that the raceway is brought suddenly into contact with the solid portion of the head surrounding the driver passage and acts to jar the nail off the ledge, the projection 94 upon the raceway serving to guide and 105 push the nail into the driver passage with its point downward.

After the nail or other fastening has been driven and the treadle has been released, the raceway will be moved into its nail-delivering position and the endmost nail of those picked up by it will slide down upon the ledge 70 into contact with the driver which is now in its lowermost position. If it is desired to drive no more nails at this 110 time, the work can conveniently be removed. If it is desired to drive another, or other, nails, the work can be moved over the horn to bring the part into which the next nail is to be inserted beneath the driver passage. 115 The raceway will remain in its nail-delivering position until the treadle is again depressed to raise the driver for the next nail-driving operation.

It will be noted that many features of the 125 construction of the machine herein disclosed are common to this machine and to the machine disclosed in my co-pending applica-

tion Ser. No. 488,031, filed April 5, 1909, which matured into Letters Patent No. 1,033,313, granted July 23, 1912. All of the common patentable subject-matter of these 5 two applications has been claimed in said Letters Patent and the present application has been restricted to features of construction patentably distinguished from the disclosure in said Letters Patent.

10 Having described my invention, what I claim as new and desire to secure by Letters Patent of the United States is:

1. In a machine of the class described, the combination with a head provided with a 15 driver passage, a driver, and a raceway pivoted to oscillate between a fastening receiving position and a fastening delivering position, of a fastening receiving ledge of such 20 dimensions that it can receive a single fastening only from said raceway when said raceway is in fastening delivering position, said ledge being so located and so shaped that it will transfer said fastening into the 25 driver passage when said passage has been cleared to receive said fastening.

2. A machine of the class described, having, in combination, a head provided with a driver passage, a stationary fastening container carried by said head, a stationary 30 fastening-sustaining ledge adjacent to, and inclined toward, said driver passage, said ledge being constructed to receive and support by its head a single fastening only, and means for taking said single fastening from 35 said container and depositing it upon said ledge.

3. A machine of the class described, having, in combination, a fastening raceway movable between a fastening-receiving and 40 a fastening-delivering position, and means for moving said raceway constructed and arranged to complete suddenly the movement of said raceway into one of the before-mentioned positions as it approaches said 45 position.

4. A machine of the class described, having, in combination, a head provided with a driver passage, a driver and a raceway pivoted to oscillate between a fastening-receiving 50 position and a fastening-delivering position and arranged to be moved into fastening-delivering position when the driver is in its lowermost position and to be moved into fastening-receiving position as the 55 driver is moved into its uppermost position, and means for effecting an oscillation of said raceway constructed to impart to said raceway a short, quick movement as it comes into fastening-receiving position.

60 5. A machine of the class described, having, in combination, a raceway movable between a fastening-receiving and a fastening-delivering position, means for effecting a gradual movement of said raceway to with-

75 in a short distance of one of said positions 65 comprising elastic means through which the moving force is transmitted to said raceway, means for checking the movement of said elastic means without checking the application of force to it whereby it is put under tension, and means for releasing the stored-up energy in said elastic means whereby the movement of said raceway into the before-mentioned position is completed suddenly.

75 6. A machine of the class described, having, in combination, a head provided with a driver passage, a fastening sustaining ledge adjacent to and inclined toward said driver passage, a driver, means separate 80 from said ledge movable into and out of a position in which it is adapted to deposit a fastening upon said ledge, and means for moving the shank of said fastening toward a position of parallelism with respect to the 85 driver as said fastening moves into the driver passage.

7 A machine of the class described, having, in combination, a head provided with a driver passage, a fastening sustaining 90 ledge adjacent to and inclined toward said driver passage, a driver, means separate from said ledge movable into and out of a position in which it is adapted to deposit a fastening upon said ledge with its head 95 in engagement with the driver, and means for moving the shank of said fastening toward a position of parallelism with respect to the driver while the head of the fastening is still in engagement with the driver. 100

8. A machine of the class described, having, in combination, a head provided with a driver passage, a driver, means for reciprocating said driver to effect a fastening driving operation, a fastening sustaining 105 ledge adjacent to and inclined toward said driver passage, means separate from said ledge movable into and out of a position in which it is adapted to deposit a fastening upon said ledge with its head in engagement 110 with the driver, and means operating as the driver is raised to permit the fastening to enter the driver passage for giving to said fastening a push toward said passage.

9. A machine of the class described, having, in combination, a head provided with a driver passage having a fastening-receiving opening in one side, a driver, a fastening-retaining ledge adjacent to said fastening-receiving opening, a raceway pivoted to oscillate between a fastening-receiving 120 position and a fastening-delivering position and provided with means for pushing the shank of a fastening supported on said ledge into the driver passage just before the 125 descent of the driver.

10. A machine of the class described, having, in combination, a head provided with

a driver passage, a stationary fastening-sustaining ledge adjacent to and inclined toward said passage, said ledge being adapted to sustain a single fastening only, means 5 for lifting and depositing a fastening upon said ledge and means for jarring said fastening into the driver passage.

11. A machine of the class described, having, in combination, a head provided with 10 a driver passage having a fastening receiving opening in one side, a driver, a fastening sustaining ledge adjacent to said fastening receiving opening, means separate from said ledge movable into and out of a position in which it is adapted to deposit a fastening upon said ledge, means for pushing the shank of the fastening sustained on said ledge toward the driver passage, and means for operating said shank pushing 20 means constructed to impart to said means a short quick stroke.

12. A machine of the class described, having, in combination, a head provided with a driver passage, a fastening sustaining 25 ledge adjacent to and inclined toward said driver passage, a driver, and means separate from said ledge movable into and out of a position in which it is adapted to deposit a fastening upon said ledge with its 30 head resting against the driver.

13. A machine of the class described, having, in combination, a head provided with a driver passage, a stationary fastening-sustaining ledge adjacent to, and inclined toward, said driver passage, and separate means for delivering fastenings singly to said ledge, said head being so constructed that a section thereof containing a portion of the driver passage and carrying said ledge 40 may be removed.

14. In a machine of the class described, the combination with a pivoted head yieldingly maintained normally in its uppermost position and provided with a driver passage, of a spring-pressed driver mounted upon said head, and means for lifting said driver so connected to said head that it effects an initial depression of the head and then a lifting of the driver.

15. A machine of the class described, having, in combination, a work support and a head movable relatively to each other into work-clamping relation and maintained yieldingly normally in a work receiving 55 rotation, a spring-impelled driver, and means for lifting said driver against the tension of the spring constructed to effect through the resistance of said spring a relative movement of said head and said 60 work support into work-clamping relation.

16. A machine of the class described, having, in combination, a work support and a head movable relatively to each other, fastening-inserting means carried by said head

and manually operated means for effecting 65 a relative movement of said work support and head into work-clamping relation to each other and simultaneously a relative movement of said fastening-inserting mechanism and said head in a different direction. 70

17. A machine of the class described, having, in combination, a work support, a head movable toward and away from said work support and provided with a driver passage, a driver mounted to reciprocate in said passage, driver-operating means mounted upon 75 said head, and means for actuating said driver-operating means constructed to effect a preliminary movement of the head toward the work support. 80

18. A machine of the class described, having, in combination, a pivoted head yieldingly maintained normally in its uppermost position and provided with a driver passage, a spring-pressed driver mounted upon 85 said head to reciprocate in said driver passage, a treadle and connections between said treadle and said head constructed and arranged to effect a lifting of said driver and an initial depression of said head. 90

19. A machine of the class described, having, in combination, a pivoted head, yieldingly maintained normally in its uppermost position and provided with a driver passage, a driver mounted upon said head to reciprocate in said passage, a spring for imparting 95 to said driver its driving momentum and a driver-lifting lever fulcrumed upon said head between the driver passage and the pivot of said head whereby when one end 100 of the lever is depressed to cause the other end to lift the driver the head will first be depressed into contact with the work.

20. A machine of the class described, having, in combination, a movable head yieldingly maintained normally in its uppermost position, a fastening driver mounted in said head and a driver spring also carried by said head, and means for lifting said driver against the tension of its spring so mounted 105 upon said head that the force necessary to overcome the resistance of the spring to the lifting of the driver effects through said means a depression of the head.

21. A machine of the class described, having, in combination, a pivoted head, a spring maintaining said head normally in its uppermost position, a driver and driver-actuating spring carried by said head, and means for lifting said driver comprising a lever 110 fulcrumed upon said head between its pivot and said driver, whereby the resistance of the driver spring to the lifting of the driver effects an initial depression of the head and a compression of the spring which maintains it normally in its uppermost position. 115

22. A machine of the class described, having, in combination, a work support and a

head provided with a driver passage and
movable relatively to said work support into
work-clamping relation thereto, manually
operated means for effecting such relative
movement, a driver and a spring for actu-
ating said driver arranged to be held out
of actuating relation to said driver during
the last part of the driving movement.

In testimony whereof I have signed my
name to this specification in the presence of 1c
two subscribing witnesses.

GEORGE GODDU.
